Des. 197,388
Patented Jan. 21, 1964

197,388

CONTAINER FOR A TOOTHBRUSH OR THE LIKE

Richard M. Hyman, Iowa City, Iowa, assignor to Weco Products Company, a corporation of Illinois

Filed Aug. 15, 1961, Ser. No. 66,361

Term of patent 14 years

(Cl. D58—12.6)

FIG. 1

FIG. 2

FIG. 4

FIG. 3

FIG. 1 is a top plan view of a container for a toothbrush or the like showing my new design;

FIG. 2 is a side elevational view thereof;

FIG. 3 is an end elevational view thereof taken from the right of FIG. 2;

FIG. 4 is an end elevational view thereof taken from the left of FIG. 2; and

FIG. 5 is a perspective view thereof on a slightly reduced scale.

I claim:

The ornamental design for a container for a toothbrush or the like, as shown.
